UNITED STATES PATENT OFFICE.

FRANK J. BAUMAN, OF DETROIT, MICHIGAN, ASSIGNOR OF ONE-THIRD TO HARRY M. LAU AND ONE-THIRD TO DEBERT M. WHITE, BOTH OF DETROIT, MICHIGAN.

AUXILIARY PROPELLER CONTROL FOR AIRPLANES.

1,287,614.

Specification of Letters Patent. Patented Dec. 17, 1918.

Application filed January 17, 1918. Serial No. 212,203.

To all whom it may concern:

Be it known that I, FRANK J. BAUMAN, a citizen of the United States, residing at Detroit, in the county of Wayne and State 5 of Michigan, have invented a new and useful Auxiliary Propeller Control for Airplanes, of which the following is a specification.

This invention relates to airplanes, and 10 particularly to means for the propulsion and control of such vehicles.

The invention has for its principal object 15 to provide improved propelling means for airplanes, especially of the bi-plane type, by which the driving power may be increased and the stability and control of the craft enhanced so as to enable the machine when in flight to be abruptly deflected laterally in its course as well as to be quickly 20 turned about in a horizontal plane.

In attaining this object the invention provides for the employment in connection with the usual forward main propeller of a bi-plane of a pair of opposed auxiliary propellers arranged transversely of said main propeller to rotate vertically at opposite ends respectively of and intermediate the upper and lower planes of the machine. These propellers are driven separately 30 through manually controlled releasable driving connections with the engine and are adapted to be operated either separately or collectively in unison with the main propeller.

One embodiment of the propelling means comprising my invention is illustrated in the accompanying drawings as applied to 35 an airplane of particular structural features constituting the subject matter of a co-pending application for patent filed by me January 4, 1918, Serial No. 210,856, and which form no part of the present invention.

In the drawings,

Figure 1 is a side elevation of a bi-plane 45 having my improved propelling means applied thereto.

Fig. 2 is a front elevation of the structure as shown in Fig. 1.

Fig. 3 is a horizontal longitudinal section 50 through the structure on dotted line 3—3 of Fig. 1.

Referring to the parts of the machine by the characters of reference on the drawings, 55 1 indicates generally the frame-work or

body, 2 the upper plane and 3 the lower plane of a craft of the bi-plane type. Mounted on the frame or body is an engine 4, and arranged at the forward end of the craft is the usual main driving propeller 5 which may be driven by the engine in any suitable manner, but is herein shown as mounted upon a horizontally journaled propeller shaft 6 which extends into a gear case 7 and carries a pinion 8 in mesh with a gear 9 on a vertical shaft 10 which is journaled in said gear case and connected by gears 11 in driving engagement with the shaft 12 of the engine.

Arranged to operate transversely of said 70 main propeller respectively at opposite ends of and intermediate the upper and lower planes 2 and 3 is a pair of vertically rotatable auxiliary propellers 13 the respective blades of which are reversely opposed in 75 angular relation and adapted to oppositely exert drawing force upon the craft transversely of its forwardly propelled course. These auxiliary propellers, which are adapted to be driven independently and collectively relatively to and in unison with the main propeller, are respectively mounted upon transverse horizontal shafts 14 which are journaled at one end each in bearings 15 on the frame 1, and extend at their opposite 80 ends through bearings 16 on the gear case 7 into axial alignment within said case. Loosely receiving the inner ends of the shafts 14 is a clutch barrel 17 carrying a gear 18 in mesh with the gear 9 of the vertical shaft 10, and engageable with the clutch barrel and splined on the respective shafts 17 are slidable clutches 19 which are normally held in driving engagement with the ends of said barrel by coiled springs 20 95 interposed between the ends of the gear case and the hubs of said clutches. The latter are each provided with a peripheral groove 21 for the reception of a shifting yoke 22 carried by a rock-shaft 23 which is journaled to extend transversely through the gear case 7 and is provided at its outer end with a crank arm 24 connected by a pull rod 25 to a pivoted foot lever 26, through the operation of which movement is imparted to retract the clutch against the tension of its spring and release the corresponding shaft from driving engagement with the clutch barrel. Thus the transmission 105 of the driving power to the auxiliary 110

propellers may be controlled to operate said propellers either singly or collectively independently of said main propeller or correspondingly in conjunction therewith.

- 5 It will now appear that when said auxiliary propellers are both in operation with the main propeller, as when the craft is under headway in flight, the action of said auxiliary propellers will tend to exert an 70
10 upward and forward lifting force upon the craft owing to the greater tractive effort induced by the blades through the upper forward arcs of their travel against the air pressure resulting from the velocity of the 15
15 forward movement of the craft than is afforded the blades through the lower arcs of their travel under the influence of such pressure. Since these propellers are arranged to operate at the extremities of the 20
20 main planes transverse to the main propeller, the lateral drawing force exerted by the former will be neutralized by their opposed action when driven together and the direction of the forward course influenced 25
25 by the main propeller will not be affected, while at the same time the lifting force exerted by said auxiliary propellers upon the ends of the main planes will assist in counterbalancing and stabilizing the craft 30
30 against axial movement in flight.

In connection with the use of the usual tail rudders, as indicated at 27 and 28 for respectively controlling the course of the craft upon the water and in the air, the 35 auxiliary propellers may be effectively utilized to enable the craft to be quickly turned or deflected in its course by operating them independently in conjunction with either or both the main propeller and steering rudder. For example, when releasing either of 40 the auxiliary propellers from driving power through disengagement of the corresponding clutch, the propeller remaining in driving engagement will exert a drawing force 45 upon the craft transverse to that of the main propeller and the craft will be deflected horizontally in a forward angular direction laterally of its course. This movement may be accelerated by the proper manipulation 50 of the steering rudder to correspondingly afford angular resistance to the forward travel of the craft, and by setting the rudder in a transverse position with one of the auxiliary propellers operating independently 55 of the main propeller the craft may be caused to turn in the arc of a circle about said rudder.

It will be understood that my improved features as described may also be applied 60 to airplanes as commonly constructed and equipped with landing gear, steering, plane warping, and stabilizing and controlling mechanisms.

What I claim is:

- 65 1. In an airplane, the combination with

the main plane and body of an aircraft, of an engine mounted thereon, a main driving propeller operatively connected with said engine, reversely opposed auxiliary propellers journaled at opposite ends of said plane 70 to rotate vertically transversely of said main propeller, and means for driving said auxiliary propellers simultaneously with said main propeller.

2. In an airplane, the combination with 75 the main plane and body of an aircraft, of an engine mounted thereon, a main vertically rotatable propeller connected in driving engagement with said engine, auxiliary vertically rotatable propellers journaled on 80 horizontal axes adjacent the ends of said plane in opposed transverse relation to said main propeller, and driving connections for operating said auxiliary propeller in union with said main propeller. 85

3. In an airplane, the combination with 90 the plane and body of an aircraft, of an engine mounted thereon, a main forward driving propeller operatively connected with said engine, vertically rotatable auxiliary propellers mounted in opposed relation respectively adjacent the ends of said plane, and engageable driving connections for selectively actuating said auxiliary propellers 95 independently with said main propeller. 95

4. In an airplane, the combination with 100 the planes and body of a bi-plane aircraft, of an engine mounted thereon, a main forward driving propeller operatively connected with said engine, vertically rotatable auxiliary propellers arranged intermediate said planes at opposite ends respectively thereof and connected for driving engagement with the engine, and manually controlled means for establishing driving connections between 105 said engine and said auxiliary propellers.

5. In an airplane, the combination with 110 the planes and body of a bi-plane aircraft, of an engine mounted thereon, a main forward vertically rotatable propeller operatively connected in driving engagement with said engine, vertically rotatable reversely opposed auxiliary propellers mounted respectively upon horizontal axis intermediate the planes adjacent the ends thereof, and 115 independently engageable driving connections between the engine and said auxiliary propellers.

6. In an airplane, the combination with 120 the planes and body of a bi-plane aircraft, of an engine mounted thereon, a main forward driving propeller operatively connected with said engine, axially aligned transverse shafts journaled intermediate said planes, reversely opposed auxiliary propellers mounted on said shafts respectively adjacent the ends of said planes, and clutch mechanism for establishing releasable driving connections between said shafts and said engine. 125 130

7. In an airplane, the combination with the planes and body of a bi-plane aircraft equipped with propelling and controlling means, of a pair of vertically rotatable auxiliary propellers arranged in reversely opposed relation intermediate said planes at opposite ends respectively thereof, and

means for operating said auxiliary propellers in conjunction with the propelling and controlling means of said aircraft. 16

In testimony whereof I sign this specification.

FRANK J. BAUMAN.
